CLEANING APPARATUS

Edward Page Anderson, Rutherford, N. J., assignor to Bendix Aviation Corporation, Teterboro, N. J., a corporation of Delaware

Application July 19, 1944, Serial No. 545,681

1 Claim. (Cl. 299—58)

1

This invention relates to cleaning apparatus generally and more particularly to novel apparatus adapted for thoroughly washing and cleansing small mechanical or other parts such as, for example, bearings, gears, shafts, lenses, etc.

In the manufacture of small mechanical parts for use in precision instruments, the parts normally accumulate foreign materials thereon such as, metal chips, lint, dust and grease films and, unless they are thoroughly cleansed prior to final assemblage, the instruments will be faulty in operation. This is especially true of small parts possessing inaccessible but critical surfaces. To the end that such small mechanical parts may be cleansed as thoroughly as possible, the present invention contemplates the provision of a novel washing and cleaning apparatus with the use of which all foreign material present on or adhering to such parts will be eliminated therefrom.

An object of the present invention, therefore, is to provide a novel washing and cleaning apparatus for cleaning small mechanical parts.

Another object of the invention is to provide a small, compact and novel apparatus of the nature described which will be portable in character.

A further object of the invention is to provide a novel method of cleaning small mechanical parts.

The above and further objects and novel features of the invention will more fully appear from the following detailed description when the same is read in connection with the accompanying drawings. It is to be expressly understood, however, that the drawings are for purposes of illustration only and are not intended as a definition of the limits of the invention.

In the drawings wherein like reference characters refer to like parts throughout the several views,

Figure 1 is a front perspective view of the novel washing and cleaning apparatus of the present invention;

Figure 2 is a schematic air flow diagram of the apparatus of Figure 1;

Figure 3 is a rear perspective view of the apparatus shown in Figure 1; and,

Figure 4 is a fragmentary detail view of a portion of the apparatus of Figure 1.

In general, the present invention contemplates the use of clean, dry and preferably heated air under pressure for spraying, in the nature of a sand blast, a solvent on to the small mechanical part or parts to be cleaned. Figure 2 of the drawings is a schematic diagram illustrating the

2

path taken by the air utilized in carrying out the objects of the present invention and, as there shown, is conveyed by a conduit 10 to the input of a moisture filter 11 through a conventional pressure regulator valve 12, the output of the filter communicating through a conventional pressure gauge 13 with the input of a second filter 14 for cleaning the air, clean and dry air being thus available at the outlet of filter 14.

10 The clean, dry air passes through a conduit 15 to the interior of a heater 16 which comprises generally an electrical resistor element 17 having one end thereof connected to a suitable source of current through a conductor 18 and the other end thereof being connected to the source through a conductor 19, a fixed contact 20 and a movable contact 21 carried by a thermoplastic element 22, the latter being designed so that at room temperature the two contacts will be in engagement.

15 20 A switch 23 is interposed in conductor 19 and when it is operated to its closed position, resistor element 17 heats up until a predetermined temperature is reached whereupon contact 21 disengages contact 20 and resistor 17 cools until contact 21 again engages contact 20 to close the circuit, a pilot lamp 24 being provided between conductors 18 and 19 to visually indicate the "off" and "on" operation of the resistor element. The outlet of heater 16 is provided with a conduit 25

25 30 to which may be tapped one or more control valves for utilizing the clean, dry and heated air passing from the heater.

35 One practical form of the novel apparatus of the present invention is shown in Figures 1 and 3 as comprising a supporting base 30 and a control panel 31 which is secured to the base by suitable means such as brackets 32, 33. Air under pressure is fed from a suitable source (not shown) to a control valve 34 which connects by way of a

40 45 pipe 35 with a conventional pressure regulator valve 36 secured to the rear of the control panel and having a control knob 37 at the front of the panel. The outlet of valve 36 communicates by way of a pipe 38 with a filter 39, which may be of the porous stone type, so that moisture present

45 50 in the incoming air is removed therefrom and collects at the bottom of the filter where it may be drained when desired, a drain valve 40 being provided to this end. A pipe 41 is provided at the outlet of filter 39 and connects with the input of a filter 42, which may be formed from bronze wool having a thin non-volatile oil film whereby the dry air passing through the filter is thoroughly cleansed. Interposed in the pipe 41 is a connection 43 leading to a pressure gauge 44 mounted

55

at the front of the control panel which indicates the amount of pressure flow in the system set in by knob 37.

The outlet of filter 42 is provided with a connection 45 having a pipe 46 connected thereto and arranged at the front of the control panel with two or more pressure taps 47 whereby cold, dry and clean air is available thereat. Another pipe 48 is also tapped to connection 45 and communicates with the interior of a heater 49, the heater having an outlet connection 50 provided with two or more pressure taps 51 mounted at the front of the control panel.

For transporting purposes, two jars 52 are normally supported on base 30 and fastened within in clamps 53 and 54 secured to the rear of the panel. In actual operation, the jars are removed from the clamps and placed in front of the apparatus with rubber tubes 55 (one of which is shown in Figure 4) joining taps 51 with nozzles 56 (Figure 4). Air nozzles 56 are surrounded by larger nozzles 57 whose interiors communicate with the interior of jars 52 by way of pipes 58. The jars being provided with a suitable solvent such as, chloroform, for example. A suitable control valve 59 is arranged in pipe 58 to shut off solvent flow to the interior of nozzle 57 when only heated air is desired at the nozzle outlet.

As shown in Figure 2, fixed contact 20 is screw threaded so that it may be adjusted as desired in its relative distance from the movable contact and to this end, a knob 60 is provided on the front of the control panel. Current is supplied to heater 49 by means of a plug 61 and a cable 62 shown in Figure 3. Also arranged on the panel is a switch 63, similar to switch 23 of Figure 2, for closing the circuit to the heater and a pilot lamp 64, similar to lamp 24 of Figure 2, for visually indicating the operation of the heater.

In operation, the operator may hold a mechanical or other part to be cleaned or stack one or more of such parts upon a suitable support and bring nozzle 57 closely adjacent the parts. Control valve 34 is opened to permit compressed air to flow in the system and knob 37 is operated until the desired pressure, as indicated by gauge 44, is attained in the system. The compressed air flows through filter 39 where all the moisture particles are removed therefrom through filter 42 where the air is thoroughly cleaned, and into heater 49 where the dry, clean air is heated. The compressed air so processed issues from nozzle 56 to impinge upon the work piece. Valve 59 will have been opened so that as air issues from nozzle 56, solvent from jar 52 flows into nozzle 57 so that the device acts in the nature of an atomizer, a fine spray of solvent and air impinging upon the work piece.

Once the part is cleaned in this manner its temperature will have fallen below room temperature so that if the air and solvent is shut off abruptly, moisture will condense on the part and cause rusting thereof. To avoid this, once the part is cleansed, valve 59 is shut off and heat-

ed air alone is permitted to impinge upon the part to raise its temperature to room temperature and thereby prevent any undesirable condensation.

5 It will now be apparent to those skilled in the art that a novel apparatus for and a novel method of cleaning small mechanical or other parts has been provided, the method comprising the steps of drying, cleaning and heating compressed air, 10 atomizing a solvent by means of the compressed air, and thereafter closing off the solvent and heating the part back to room temperature.

Although but one embodiment of the invention has been illustrated and described in detail, it is 15 to be expressly understood that the invention is not limited thereto. Various changes can be made in the design and arrangement of the parts without departing from the spirit and scope of the invention as the same will now be understood by those skilled in the art. For a definition of the limits of the invention, reference will be had primarily to the appended claim.

I claim:

25 A washing and cleaning apparatus utilizing compressed air comprising an air drier, an air cleaner, and an air heater interconnected in series by pipes to the source of compressed air for drying, cleaning and heating the air; a tap-off connection in the pipe interconnecting said air cleaner and said heater, at least two pressure taps, one connected to the tap-off connection for clean, dry air and the other connected to the pipe leading from the heater for clean, dry and heated air; a plurality of solvent containers, a nozzle fixed to each of said pressure taps, and solvent bearing nozzles connected to said solvent containers surrounding said first nozzles whereby a fine spray of solvent issues with the air stream.
